CLAIM

The ornamental design for a LED strip light, as shown and described.

DESCRIPTION

FIG. 1 is a front, right side, top perspective view of an LED light strip showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines depict portions of the LED light strip that form no part of the claimed design.

The drawings contain symbolic breaks that are depicted by dot-dash-dot break lines. The dot-dash-dot lines and the portion between the break lines form no part of the claimed design.
